UNITED STATES PATENT OFFICE.

GURN S. WEBB AND OLOF B. ANDERSON, OF MARQUETTE, MICHIGAN.

ANIMAL-PROOF GARBAGE-CAN.

1,296,576.

Specification of Letters Patent.

Patented Mar. 4, 1919.

Application filed September 5, 1916. Serial No. 118,392.

To all whom it may concern:

Be it known that we, GURN S. WEBB and OLOF B. ANDERSON, citizens of the United States, residing at Marquette, in the county 5 of Marquette and State of Michigan, have invented a certain new and useful Improvement in Animal-Proof Garbage-Cans, of which the following is a full, clear, concise, and exact description, reference being had 10 to the accompanying drawings, forming a part of this specification.

Our invention relates to animal proof garbage cans, and has for its object the provision of a garbage or refuse can of this character which during use may remain closed and not susceptible to the annoying situation of having its contents thrown about whenever the can is upset. It is, of course, imperative that cans which contain refuse be 20 and remain in a closed condition not only to prevent offensive odors, but also for sanitary reasons, and furthermore to prevent the breeding of mosquitoes, flies and other pests which breed in the presence of refuse or 25 stagnant liquids.

Our invention therefore has for its object the provision of a can or receptacle of this character which has means whereby the entire top portion thereof may be removed for 30 purposes of emptying, this top being held in place by means quite secure, to be unfastened only when emptying the can. This top then carries a further closure or lid which by an easily operable catch can be suitably opened 35 and closed rapidly if desired for the purpose of introducing garbage or refuse into the interior of the can.

We will explain our invention more in detail by referring to the accompanying drawing, 40 illustrating one embodiment thereof, in which Figure 1 is a top view of a can constructed in accordance with our invention;

Fig. 2 is a sectional view on line *a—a* of Fig. 1; and

Fig. 3 is a fragmentary side view more clearly illustrating the catch for holding the top in position.

Our improved structure includes a preferably cylindrically shaped can 1, desirably 45 made of metal which is adapted to hold the cover 2 in position. This cover preferably has a reinforced portion 3 thereby to maintain its circular outline. The lower portion of this cover is rounded as shown at 55 further to strengthen it, thus providing a

rounded rib or rim. The cover is held in place upon the can by means of two catches 5 and 6 which form parts of the spring plates 5^a and 6^a. These catches are pressed in position by means of finger pieces 7 in the 60 form of cams held upon the spindles 7^a. By rotating the right hand finger piece 7 (Fig. 2) in a contra-clockwise direction the cam portion thereof is taken out of the path of the spring catch 6, thus permitting the upper part of the spring catch 6 to move to the right to release the cover. It will be readily seen that the catches 5 and 6 can be swung about their pivots to hold the cover in place, or may be swung outwardly to release the 70 cover. Thus when it is desired to empty the can the catches 5 and 6 are released so as to remove the entire cover whereupon the contents may be readily removed. It is, of course not desirable to use means of this 75 character when merely introducing the material into the can, and for this reason a more quickly operable structure is utilized, which structure normally holds in a closed position the lid 9. This lid by means of the 80 arms 10 is pivotally supported upon a spindle 11. The opposite end of the cover has a latch 12 pivoted at 13, as shown, and suitably confined in its movements by the guide 14. This latch 12 coöperates with 85 the arm 15 to hold the lid normally in a closed position. It will likewise be seen that the annular opening 16 in the top is bent upwardly to coöperate more thoroughly with the rounded rim 17 of the lid, thus to form a 90 perfect closure.

From what has thus been described the nature of our invention will be readily clear to those skilled in the art. Having, however, thus set forth one embodiment which 95 our invention may take, what we claim as new and desire to secure by Letters Patent is:

A device of the character described, comprising a can, a removable cover for said can, a strengthening rib for the cover disposed on the exterior thereof, locking mechanism including a spring finger for holding the cover in closed position on the can, said 100 spring finger being secured to the can and 105 adapted to engage on the outer side of said strengthening rib of the cover, a cam for forcing the spring finger into locking engagement with the reinforcing rib, and a reinforcing rim for the cover extending 110

around the inner face thereof at the inner side of said strengthening rib, said reinforcing rim being constructed to seat upon the can and to determine the position of the 5 strengthening rib relative to the spring finger.

In witness whereof, we hereunto subscribe

our names this 18th day of August A. D., 1916.

GURN S. WEBB.
OLOF B. ANDERSON.
